ROBERT S. A. DOUGHERTY AND NEIL E. SALSICH, OF BETHLEHEM, PENNSYLVANIA, AS
SIGNORS TO BETHLEHEM STEEL COMPANY.

ANTICREEPER DEVICE.

Application filed July 15, 1926. Serial No. 122,533.

Our invention relates to anchoring or anti-creeper devices, and particularly to the type which extend beneath the base, of a railroad rail, gripping same and so positioned as to coact with a tie of the trackway to check the creeping tendency of the rail.

Our invention has for one of its objects the provision of a novel and improved form 10 of anti-creeper device which is easily applied to the rail base and efficiently grips same to check the creeping tendency of the rail.

A further object of our invention is the 15 provision of a two-piece anti-creeper device so constructed that the pieces may be shipped in their correct assembled relation to each other and in such a manner that they are not liable to be separated and are ready 20 for immediate use.

A further object of our invention is the provision of anti-creeper device in which an 25 efficient grip of the rail base is initially attained independent of creeping action of the rail.

A further object of our invention is the provision of a substantially rigid anti-creeper device adapted to effectively grip 30 the base of new and worn or corroded rails alike.

A further object of our invention is to provide an anti-creeper device adaptable to rails having base flanges of different widths and thicknesses.

The novel features of our invention will 35 be more fully understood from the following description and claims taken with the drawings, in which:

Fig. 1 is a side elevation of our anti-creeper device in position to be applied to 40 the rail base;

Fig. 2 is a side elevation of our anti-creeper device in its loose position on the rail base;

Fig. 3 is a side elevation of our anti-creeper device in its gripping position after 45 the key member has been driven;

Fig. 4 is a side elevation of our anti-creeper device as shipped illustrating in 50 broken lines the manner in which the key member is assembled with the yoke member;

Fig. 5 is a side elevation of the yoke portion;

Fig. 6 is an end elevation of the device shown in Fig. 4;

Fig. 7 is a plan view of the key member;

Fig. 8 is a longitudinal cross section of

the key member; and,

Fig. 9 is an end view of the key member.

Referring to the drawings: 10 indicates 60 a rail and 11 a tie of a railroad trackway. 12 is the yoke member and 13 is the key member of our anti-creeper device. The yoke 12 comprises a transverse under rail portion 14 and inturned hook end portions 65 15 and 16, respectively. The yoke is preferably of sheet metal shaped by stamping or shearing. The key member 13 is preferably formed from a rolled channel shaped bar which is sheared to length to provide individual key members.

The portion 14 of the yoke 12 is dropped sufficiently below the plane of the rail base to provide for a clearance and room for the 75 reception of the key member 13, and, for further clearance in applying the yoke on to the rail base transversely of the latter.

To this end, the interior or clearance space is preferably extended outwardly and downwardly below the hook portion 15 as 80 designated by the numeral 17 in Fig. 2, and thus allows this end to engage over the rail base first by tilting the yoke and then shifting it laterally on to the rail in the manner which will be readily understood from 85 Fig. 1.

The hook end 16 is then raised vertically until the underside of the hook is coplanar with the upper surface of the rail base. The yoke is then moved towards the left into 90 its position illustrated in Fig. 2. Beneath the hook end 16 there is preferably provided an abutment face 18 to bear solidly against the edge of the rail and serves to limit the movement of the yoke towards the left, 95 transversely with respect to the rail. In this position of the yoke, the upper edge of the portion 14 is substantially parallel with the bottom of the rail base for the major portion of its length. This upper edge is provided with one or more protuberances or projections 19 which are preferably 100

curved and equi-distant apart for the purpose hereinafter described.

A slot 20 is formed in the vertical edge 21 of the yoke. The lower horizontal wall 5 of the slot 20 constitutes shoulder 20' which is substantially in alignment with the tip or upper surface of the protuberances 19. The key member 13 comprises a web portion 22 having depending longitudinal leg portions 23 formed at the marginal edge thereof. The web portion 22 of the key member 13 has formed on its under surface, one or more ways 24 which are inclined in the longitudinal direction, the number of such ways depending upon the number of protuberances 19 formed on the yoke with which they are adapted to engage. The inclined ways 24, as shown in the drawings, are formed by de- 10 forming the web portion between dies. How- 15 ever, it will be understood that ways 24 suitable for the purpose may be formed by other means well known to the art of metal work- 20 ing. As shown, the leg portions 23 are spaced apart a distance slightly greater than 25 the thickness of the yoke member and when the anti-creeper device is in operative en- 30 gagement with the rail base they constitute rigid retaining members which engage the sides of the yoke to prevent lateral relative movement between the latter and the key member.

A closed end slot 25 is formed in the web portion 22 of the key member at a point somewhat beyond the transverse center line 35 and extends along the key member, but terminates at a point short of the end thereof. From a point approximately midway be- 40 tween the end of the slot 25 and the end of the key, the metal of the web is depressed or enlarged to provide an offset or hump portion 26 adapted to engage the lower horizontal wall 20' of the slot 20 for the purpose hereinafter described.

The key 13 is assembled on the yoke 12 45 in such a manner that it is not liable to be separated in shipment and the device is ready for immediate use. In this respect, the present device is an improvement over former types of two-piece anti-creeper devices which 50 are not usually shipped with the individual parts in their assembled relation. In order to assemble the key on the yoke it is inverted, as shown in broken lines in Fig. 4 and the hook end portion 15 of the yoke is 55 placed in the slot 25, as indicated by broken lines 13'. The key is moved laterally toward the yoke with a slight upward tilting movement until it is in juxtaposition with the clearance 17. It is then moved longitudinally to the left, until the end wall of 60 the slot 25 abuts the inner surface of the yoke and is then given an upward rotary movement in a counter clockwise direction and at the same time a slight movement to- 65 ward the right so that it passes around the

bottom left hand corner of the yoke on to the portion 14. The key is moved along the latter and is rotated about the bottom right hand corner of the yoke and over the top of the hook end 16 into its shipping position, indicated by full lines in Fig. 4.

Preparatory to applying our device to the rail base, the key is moved to its extreme right hand position shown by broken lines in Fig. 5 and by full lines in Fig. 1. The yoke is mounted on the rail base in the manner previously described, to its position shown in Fig. 2, and is moved longitudinally of the rail into juxtaposition with the tie 11. In this initial position of the device, it will be seen by referring to Figs. 2 and 5 that the protuberances 19 are disposed at the foot of the inclined ways 24 and the key is in its lowermost horizontal position with respect to the plane of the bottom of the rail and in this position provides a clearance indicated by the numeral 27, between the latter and the upper surface of the key member. In consequence of such clearance, the device is adaptable to fit rails having different base flange thicknesses and widths. It will also be noted that in the initial position of the key member that the offset portion 26 is not in engagement with shoulder 20' and that this end of the key extends well beyond the vertical right hand edge of the yoke. The extending end of the key is conveniently placed so that it may be struck by a hammer or other implement suitable for the purpose of driving the key transversely of the rail and longitudinally of the yoke. It will be noted that no special tool is required to drive the key member and in lieu of the hammer aforementioned, any suitable trackway accessory, such as a rail joint, tie plate, or even a piece of ballast, may be successfully used for this purpose.

As the key is driven transversely of the rail, the abutant face 18 bears solidly against the edge of the rail and prevents the movement of the yoke member in the same direction. As the key moves longitudinally on the yoke it is positively guided by the depending leg portions 23 and the inclined ways 24 engaging the protuberances 19 cause the key to be raised in right lines upwardly so that the upper surface of same is maintained parallel with respect to the bottom surface of the rail. The key is forced in contact with the latter and causes the device to firmly grip the rail. In this position, the offset portion 26 rests on the shoulder 20' and thus provides a firm support for the extending end of the key member and prevents any tendency of the key to rock about its transverse axis. It will be seen that the key member is of considerable length, compared with the length of the under rail portion 14, and when our device effectively engages the rail the key extends

almost entirely across the bottom of the rail and imparts thereto an upward bearing pressure which is uniformly distributed and secures a strong gripping action on rail.

5 In a trackway construction wherein tie plates (not shown) are employed to provide a bearing for the rail upon the tie, the space between the rail and the latter by virtue of such construction is usually sufficient to accommodate the extending edge of the key member and allow the face of the yoke to bear directly against the side face of the tie when the device is first applied to the rail. However, when the trackway construction is such that the rails bear directly on the tie, as shown in Fig. 6, the yoke, under such conditions, is initially spaced a slight distance from the tie, owing to the projecting edge of the leg portion of 20 the key member first contacting with the corner of the tie. However, in service, under the latter condition, as the rail begins to creep, the high bearing pressure developed causes said edge to bite into the 25 tie and allows the full length of the yoke to bear against the tie and provide a substantial bearing surface to coact with the tie to effectively check any further tendency of the rail to creep.

30 From the foregoing description it will be seen that we have devised an anti-creeper device which is rigid in construction and efficiently grips the rail independent of the creeping tendency of the latter and has an 35 extended bearing surface in contact with the under side of the rail base in directions both longitudinally and transversely of the rail. The key member, by the adequate support afforded by protuberances 19 of the 40 yoke member along its length, is maintained parallel at all times with respect to the plane of the bottom of the rail and thus effectively prevents any tendency of the device to rock about the rail base which 45 might otherwise occur due to non-uniformly distributed blows received in service which are occasioned by the pounding of the device on frozen ballast. Furthermore, the key member is extended beyond the rail base 50 and is accessible to the track operator so that it is conveniently driven without the use of special tools. The extended end of the key is held in the slot formed at the vertical edge of the yoke to limit reverse bending 55 in the vertical plane which might otherwise occur in service and cause the loosening of the key member.

A device constructed in accordance with our invention is conveniently shipped ready for use and in this respect is comparable with the so-called one piece anti-creeper but, however, has many advantages over the latter type, for instance, a single piece device becomes ineffective when the rail to 60 which it is applied becomes worn or cor-

roded and must be replaced, whereas, a device embodying our invention may be rendered just as effective as when originally applied to the rail by merely driving the key member with any suitable implement 70 which may be at hand. Thus a track walker observing a loose anti-creeper embodying our invention may easily place it in an effective condition without replacements or the use of special driving tools. 75

While we have shown our invention in but one form it will be obvious to those skilled in the art that it is not so limited, but is susceptible of various other changes and modifications without departing from 80 the spirit thereof, and we desire, therefore, that only such limitations shall be placed thereupon as are imposed by the prior art or as are specifically set forth in the appended claims. 85

Having thus described our invention what we claim as new and desire to secure by Letters Patent is:

1. An anti-creeper for rails, comprising a member adapted to extend beneath the rail and having portions thereof extending inwardly over the base flange of the rail, and a rigid member disposed in the vertical plane of said portions and extending beyond the edge of said base flange adapted to be 90 driven between the bottom of the rail and the first mentioned member.

2. An anti-creeper for rails, comprising a member adapted to extend beneath the rail and having portions thereof extending inwardly over the base flange of the rail, a rigid member disposed in the vertical plane of said portions and extending beyond the edge of the base flange adapted to be driven 100 between the bottom of the rail and the first mentioned member, and means to prevent substantial relative lateral movement between said members. 105

3. An anti-creeper for rails, comprising a member adapted to extend beneath the rail and having portions thereof extending inwardly over the base flange of the rail, one or more raised portions formed on said member, a member adapted to be driven between the bottom of the rail and the first mentioned member, and one or more inclined 110 ways formed on the second mentioned member for engaging said raised portions. 115

4. An anti-creeper for rails, comprising a yoke having hook ends to engage the upper surface of the base flange of the rail, and an under rail portion in spaced relation with respect to the bottom of the rail, one or more protuberances projecting upwardly from said portion, a key having a relatively large 120 bearing surface for engaging the under surface of the rail base, and one or more inclined ways formed on said key adapted to engage said protuberances. 125

5. An anti-creeper for rails, comprising a 130

- yoke, a key extending longitudinally of said yoke and having a closed slot to receive the yoke, and members depending from said key for engaging the sides of said yoke.
5. An anti-creeper for rails, comprising a yoke having one or more protuberances formed thereon, and a key member having one or more inclined ways formed thereon adapted to engage said protuberances.
10. An anti-creeper for rails, comprising a yoke having one or more protuberances formed thereon, a key member having one or more inclined ways formed thereon adapted to engage said protuberances, and members depending from said key for engaging the sides of said yoke.
15. An anti-creeper for rails, comprising a yoke having hook ends and an under rail portion, one or more protuberances formed on said portion, one edge of said yoke being slotted to provide a shoulder, a key member having a closed slot receptive of one of the hook ends aforesaid, one or more inclined ways formed on said key for engaging said protuberances, and an offset portion of said key adapted to engage said shoulder.
20. An anti-creeper for rails, comprising a yoke and a key member having a closed slot formed therein receptive of said yoke, said key being of such a length that it extends beyond the edge of the rail base when the yoke is mounted on the rail.
25. An anti-creeper for rails, comprising a yoke having a rail engaging portion and a key disposed in the vertical plane of said portion and having a slotted end portion adapted to straddle said yoke and extend beyond the edge of the rail base when the yoke is mounted on the rail.
30. An anti-creeper for rails, comprising a yoke having a rail engaging portion, a key having a slotted end portion adapted to straddle said rail engaging portion and extend beyond the edge of the rail base when the yoke is mounted on the rail, and means for moving said key into contact with the base of the rail upon movement of the key transversely of the rail.
35. An anti-creeper for rails, comprising a yoke, a key having a slotted end portion adapted to straddle said yoke and extend beyond the edge of the rail base when the yoke is mounted on the rail, and means for moving said key into contact with the base of the rail upon movement of the key transversely of the rail.
40. An anti-creeper for rails, comprising a yoke having an interior portion defining hook ends and an under rail portion, a projection extending from said under rail portion into said interior, a key member adapted to rest on said projection and having an inclined way adapted to coact with said projection to raise said key when the latter is moved longitudinally, and means to prevent lateral displacement of the key with respect to said yoke during said movement.
45. An anti-creeper for rails, comprising an interior portion defining hook ends and an under rail portion, a projection extending from said under rail portion into said interior, a key member adapted to rest on said projection and having an inclined way adapted to coact with said projection to raise said key when the latter is moved longitudinally, said key being of sufficient length to extend beyond the edge of the base of the rail upon which the yoke is mounted, and means to prevent lateral displacement of the key with respect to said yoke during said movement.
50. An anti-creeper for rails, comprising a yoke having hook ends and an under rail portion, one or more projections extending from said portion, a key having a web portion and depending leg portions, said web portion being provided with an inclined way and slotted from a point beyond its transverse center line to a point terminating short of its end and having an offset portion intermediate the slot thus formed and said end, and a shoulder formed at the vertical edge of said yoke adapted to support the end of said key when the anti-creeper is mounted in its operative position on the rail.
55. An anti-creeper for rails comprising a yoke having hook ends and an under rail portion, one or more projections extending from said portion, a key having a web portion and depending leg portions, said web portion being deformed to provide an inclined way and slotted from a point beyond its transverse center line to a point terminating short of its end and having a depressed portion intermediate the slot thus formed and said end, and walls defining a slot formed at the vertical edge of said yoke adapted to limit the vertical movement of the end of said key when the anti-creeper is in its operative position on the rail.
60. An anti-creeper for rails, comprising a yoke for an anti-creeper for rails, comprising an under rail portion, hook end portions adapted to extend over the upper surface of the rail base, and one or more protuberances formed on said under rail portion, the vertical edge of one of said end portions being slotted to provide a shoulder.
65. A key for an anti-creeper for rails, comprising a web portion, and depending leg portions, said web portion being deformed to provide one or more inclined ways.
70. A key for an anti-creeper for rails,

comprising a web portion, and leg portions, said web portion having a protuberance constituting an inclined way and having a certain portion of its length removed to constitute an elongated slot.

20. An anti-creeper for rails, comprising a yoke adapted to extend beneath the rail and having portions thereof extending inwardly over the base flange of the rail, and 10 a key member adapted to straddle said yoke and to be driven between said yoke and the bottom of the rail, said key member being of such length that upward bearing pressure is applied to the bottom of the rail across 15 substantially the entire width of its base flange and in the same vertical plane as the downward pressure applied to the upper surface of the flange by the aforesaid portions when the anti-creeper is in its operative 20 position on the rail.

21. An anti-creeper for rails, comprising a yoke having hook ends and an under rail portion, one or more protuberances formed on said portion, a key member having a 25 closed slot receptive of one of the hook ends aforesaid, one or more inclined ways formed on said key for engaging said protuberances, and a shoulder formed at a vertical edge of said yoke for engaging said key 30 when the anti-creeper is mounted in its operative position on the rail.

22. An anti-creeper for rails, comprising a yoke having hook ends and an under rail portion, a key member adapted to coact with 35 said portion whereby it moves upwardly against the rail base when driven transversely with respect to the rail, and a shoulder formed at a vertical edge of said yoke for supporting said key member when the 40 anti-creeper is mounted in its operative position on the rail.

23. An anchor for rails comprising a yoke having an under rail portion connecting a pair of hook end portions, and a key member having an opening formed therein, one 45 of said hook end portions and said under rail portion being so formed with respect to said opening that this end portion of the yoke may enter said opening and the key 50 then moved along the under rail portion to its position preparatory to applying the anchor to a rail and the other hook end portion being so formed with respect to said opening as to prevent the removal of the 55 key member from the yoke at the last mentioned portion.

24. A two-piece anchor for rails comprising a member having an under rail portion and a rail flange engaging portion, a vertical 60 portion connecting the first mentioned portions, a key member embracing said vertical portion and adapted to lie upon said under rail portion beneath said rail flange engaging portion, and means to prevent the re-

moval of said key member from said member over said rail flange engaging portion.

25. An anchor for rails comprising a member adapted to extend beneath the rail and having a portion thereof adapted to engage the base flange of the rail, and a 70 member adapted to be driven between the bottom of the rail and the first mentioned member, one of said members having one or more raised portions and the other member having one or more inclined ways for 75 engaging said raised portions.

26. An anchor device comprising a member having a body portion and a hook end portion extending from said body portion, and a key member adapted to lie upon the 80 latter portion and straddle said hook end portion.

27. An anchor device comprising a member having a hook end portion, a key having a slotted end portion adapted to rest on 85 said member and straddle said hook end portion, and means for moving said key laterally with respect to said member upon longitudinal movement of the key.

28. An anchor for rails comprising a member having a flange engaging portion, a key having a slotted end portion adapted to straddle said flange engaging portion and extend beyond the edge of the rail base when said member is mounted on the rail, and 95 means for moving said key into contact with the base of the rail upon movement of the key transversely of the rail.

29. In a railway track structure the combination of a tie, rail supported on said tie, 100 a member disposed transversely under said rail and having a flange engaging portion, and a key interposed between said member and the rail and extending beyond the edge of the rail base and straddling said flange 105 engaging portion.

30. An anchor device comprising a member having a body portion and a portion extending from said body portion, and a key member resting on said body portion and 110 embracing said extending portion so that the parts may be shipped assembled together in the relationship they have to each other preparatory to applying them to their effective position.

31. A yoke for a rail anchor, comprising a plate of substantially uniform thickness adapted to lie flat against a railroad tie and having a reentrant portion defining hook ends and an under rail portion and a plurality of curved members extending from said under rail portion into said reentrant portion.

In testimony whereof we hereunto affix our signatures.
